US00D336890S

United States Patent [19]

Hirose et al.

[11] Patent Number: Des. 336,890

[45] Date of Patent: ** Jun. 29, 1993

[54] GEARED MOTOR

[75] Inventors: Hideo Hirose; Yutaka Tsutsui; Hiroshi Hasegawa, all of Osaka, Japan

[73] Assignee: Matsushita Electric Industrial Co., Ltd., Osaka, Japan

[**] Term: 14 Years

[21] Appl. No.: 716,600

[22] Filed: Jun. 17, 1991

[30] Foreign Application Priority Data

Dec. 25, 1990 [JP] Japan 2-43119

[52] U.S. Cl. D13/112

[58] Field of Search D13/112; 310/83, 89; 74/425
